RING SPINNING FRAME

Jose Serra Sio, Barcelona, Spain

Application March 10, 1938, Serial No. 195,036
In Spain March 23, 1937

8 Claims. (Cl. 57—110)

This invention relates to improvements in spinning frames of a type generally known. In this well known type of spinning frame, as heretofore constructed, transversely arranged cast metal frames or "sampsons" are placed at suitable distances from each other throughout the length of the frame, the number of "sampsons" mounted in the frame depending upon the length of the frame and the number of spindles therein. 10 These cast metal "sampsons" are connected together by suitable framing members and support the spindle rails. In order to properly align the mechanism of the spinning frame these cast metal "sampsons" are necessarily very carefully machined and accurately aligned throughout the 15 spinning frame. This requires accurate manufacture and careful and accurate setting up of the frame.

In this type of spinning frame the reciprocal vertical motion of the ring-rail, or "builder motion," is secured through the oscillation of cross shafts which are connected to the ring-rails by means of levers, the free ends of which have a reciprocal vertical motion and are connected to the ring-rails by suitable rods. This form of "builder motion" results in imparting to the ring-rail variable speeds in the course of its vertical movement. This variation in the speed of the movement of the ring-rail is due to the fact 20 that the levers swing in an arc and move vertically faster at certain points in that arc than at other points in the arc. Due to this variable speed in the movement of the ring-rail the bobbin or yarn package has a larger diameter at its 25 ends and a smaller diameter about the middle of the bobbin or yarn package. The smaller diameter at the middle part of the bobbin is due to the fact that because of the arrangement of the arms or levers which give vertical motion to the ring-rail the ring-rail travels faster when 30 at about the middle of the bobbin, or about midway the height of the spindle, and travels slightly slower when the ring-rail approaches the limits of its up and down movements. This defect is increased as the traverse of the ring-rail is 35 increased. Because of the variation of speed in the vertical movement of the ring-rail there is a variation in the tension on the yarn and this results in a rapid wearing out of the spinning 40 rings and the spindles.

It is the main object of this invention to produce a spinning frame free of the objections and disadvantages of the old and well known spinning frame as herein set forth.

Another object of the invention is to provide

means whereby the ring-rail will be given a uniform and constant speed throughout its up-and-down movement or traverse.

A further object of the invention is to provide means whereby the length of the up-and-down movement or traverse of the ring-rail may be varied in order to adapt the spinning frame for use with spindles of various lengths while at the same time producing a bobbin or yarn package of uniform diameter.

A further object of the invention is to provide means whereby the thread board carrying the thread guides is given a directly vertical up-and-down movement at a constant uniform speed and in a definite ratio to the up-and-down travel of the ring-rail; to provide means whereby when the traverse of the ring-rail is varied the traverse of the thread board carrying the thread guides will be correspondingly varied while maintaining the desired definite ratio of travel between the thread board and the ring-rail.

A further object of the invention is to provide a construction of the spinning frame that will permit the manufacture of the parts in standard forms and lengths, whereby the spinning frame may be formed of any desired length for any desired number of spindles by merely assembling the standard parts in groups, the various supporting members being vertically adjustable on vertical standards of uniform shape in order to properly align and level off all parts of the machine.

Another object of the invention is to provide vertical supporting standards which will serve not only as supporting elements for the machine and the parts thereof, but will also serve as guiding and supporting means for movable parts of the machine, such as the ring-rail and the thread board.

Other objects and advantages of the invention will appear hereinafter.

In the drawings, Fig. 1 is a diagrammatic elevation of a portion of the spinning frame constructed in accordance with my invention;

Fig. 2 is an end elevation of the head end of the spinning frame construction illustrated in Fig. 1; and

Fig. 3 is a transverse vertical sectional view of the spinning frame constructed in accordance with this invention.

Referring to the various parts by numerals, 1 designates the head end of the spinning frame in which is mounted the mechanism for rotating the longitudinal shafts hereinafter described for imparting movement to the various mecha-

nisms of the spinning frame. This mechanism is not shown as it forms no part of the present invention. Any suitable mechanism may be employed for driving the longitudinal shafts for imparting movements to the spindles and the other mechanisms hereinafter described.

The reference characters 4 designate vertical bars of any desired cross-sectional shape which form the standards or supports for the spinning frame. These standards or columns 4 are arranged in pairs transversely of the machine and the bars are located convenient distances apart from end to end of the spinning frame. The lower ends of each pair of columns 4 are mounted in transverse base pieces or connecting bars 6, said bars being provided with sockets on their upper surfaces to receive the lower ends of the columns. Each base piece is provided with outwardly extending lugs at its ends and through said lugs are threaded leveling screws 6''. The lower ends of these screws are provided with bearing plates adapted to rest on the floor in order to give an adequate support for the base piece. The upper ends of each pair of columns are connected together by a transverse bridge piece 6', the upper ends of the columns fitting in sockets formed on the under surface of the bridge piece.

The sets of columns connected together transversely of the machine are connected together longitudinally of the machine by angle plates 5 secured to the ends of the bridge piece 6' and extending throughout the length of the frame. These angle pieces 5 form the bases or supports for the roll stands 5'.

Rigidly secured to the standards or columns 4 are spindle-rail-supporting brackets 9. These brackets are formed with tubular sockets 9' adapted to closely fit the columns and are clamped thereon by bolts 9''. The brackets extend outwardly from the sockets and the spindle rail 8 is bolted to the outer vertical faces of the brackets. The spindle-rail-supporting brackets may be vertically adjusted on the columns to place the spindle rail at the proper height and also to line it up horizontally throughout the length of the spinning frame. An outwardly facing spindle-rail bracket is mounted on each standard so that there is a spindle supported on each side of the spinning frame. The spindles are mounted on the spindle frame on suitable spindle bearings and are provided with the usual driving pulley over which the spindle-driving tape passes.

Secured to the under surface of the spindle rails and extending transversely across the machine are a series of bars 27, said bars connecting together the spindle rails on opposite sides of the machine and serving as supports for the bearings of the longitudinally extending drum shaft 27'. On this shaft is secured the drum 27'' around which the spindle-driving tapes 28 run. A tape-tensioning device 26 is mounted on one of the spindle-rail-supporting brackets 9 for each spindle-driving tape, a weight 26' being provided to exert a constant tension on the tape through tape-tensioning means. This is common in spinning frames of this type and it is thought to be unnecessary to illustrate in detail the construction of the tape-tensioning device. It is manifest that by adjusting the spindle-rail-supporting brackets 9 up and down on the column 4 the spindles, the spindle-driving tapes and their tensioning means, and the tape-driving drum will

all be moved together and without varying their relative adjustment with respect to each other.

Depending from the upper bridge pieces 6' are supporting brackets 11 in the lower ends of which is journaled a longitudinally extending builder-motion shaft 12. This shaft is given a rotary oscillating motion by suitable mechanism arranged at the head end of the machine. Any suitable automatically reversing means may be employed for this purpose and it is thought to be unnecessary to illustrate this mechanism. On the shaft 12 are secured a number of large ring-rail-moving pulleys 14 which are spaced apart suitable distances along the shaft, the said shaft extending throughout the length of the spinning frame and the number of pulleys mounted thereon being dependent upon the length of the spinning frame. On the columns 4, above the spindle-rail-supporting brackets 9, are arranged vertical slides 16, said slides accurately fitting the columns and being arranged to slide up and down thereon. Near the lower ends of the columns and below the brackets 9 are arranged slides 16' which are similar to slides 16 and are adapted to slide up and down on the columns. Each pair of slides on each column is connected together by a vertical rod 17, said rod being arranged on the outer side of the adjacent column 4. The slide 16 of each pair is connected by a chain 13 to a cooperating pulley 14, the chain 13 running over a pulley 15 mounted in a bracket 15' connected to the top of the column and extending inwardly beyond the column. Connected to the upper end of the rod 17 just above the slide 16 is an outwardly extending ring-rail-supporting bracket 18. 18 designates the ring-rail which is secured to the outer ends of the brackets 18 and normally lies above the spindle pulleys. There is a set of slides 16-16' for each column 4, and each set of slides carries a rod 17 and a ring-rail-supporting bracket 18.

The chain 13 from the ring-rail-supporting slide on one side of the machine contacts the pulley 14 at one side of its center, while the chain 13 from the other side of the machine contacts the pulley 14 on the opposite side of its center, so that the rotation of the pulley 14 in one direction will result in the simultaneous upward movement of the ring-rails on opposite sides of the machine and the reverse rotation of the pulley 14 will result in the simultaneous downward movement of the ring-rails on opposite sides of the machine. The ring-rails are guided in their up-and-down movements by the slides arranged on the columns 4 and said ring-rails move at a constant or uniform speed at all points in their travel both up and down. The extent of the up-and-down movement of the ring-rails is governed by the extent of rotation of the shaft 12. It is only necessary to provide means for rotating the shaft 12 a certain extent in one direction and then automatically reversing and rotating it the same extent in the opposite direction to provide the desired length of traverse for the ring-rails.

The thread board 24, carrying the thread guides 21' directly over the vertical axis of the spindle, is mounted on a series of vertically movable rack bars 24. These rack bars are mounted to slide upwardly and downwardly in guides formed in the outer face of the brackets 22 secured to the upper ends of the columns 4. Rotatably mounted in each bracket 22 is a gear wheel 23 which meshes with the teeth of the rack bar. On the shaft of the gear wheel is mounted a small pulley 23' over which runs a

chain 20, one end of said chain being connected to the pulley 23'. The other end of this chain 20 is connected to and winds about a small thread-board-moving pulley 19 mounted on the shaft 12. The chain 20 from the pulley 23' on one side of the machine contacts the pulley 19 at one side of its center while the chain 20 from the other side of the machine contacts the pulley 19 on the opposite side of its center, so that the rotation of the shaft 12 in one direction will result in an upward movement of the thread board carrying the thread guides and the rotation of the shaft 12 in the opposite direction will result in a downward movement of the thread board.

16 The pulleys 14 and 19 are so proportioned with respect to each other that the desired ratio of movement between the ring-rail and the thread board will be secured. The movements of the ring-rail and the thread board are controlled 20 through the rotation of a single shaft in order to secure the simultaneous reversal of movement of the two ring-rails and the two thread boards.

25 The brackets 22 supporting the thread boards may be adjusted on the columns 4 to locate the thread guides in proper relation to the upper ends of the spindles.

30 The ring-rails and the thread boards may be counter-balanced in any suitable manner, as is customary in machines of this type. Upon the reversal of the direction of rotation of the builder-motion shaft the ring-rails and the thread-boards drop by gravity, the speed of the downward movement being controlled by the speed of rotation of the builder-motion shaft.

35 What I claim is:

1. A spinning frame comprising a series of vertical standards spaced suitable distances apart and arranged in pairs transversely of the machine, a transverse connecting base piece for 40 each transverse pair of columns and supporting said columns, a transversely extending bridge piece connecting the upper ends of said pair of columns, longitudinally extending roll-stand-supporting members secured to the ends of the 45 bridge pieces directly over the upper ends of the said columns, outwardly extending spindle-rail-supporting brackets secured to and vertically adjustable on said columns at each side of the machine frame, a spindle rail on each side of the machine frame and supported by said spindle-rail brackets, spindles supported by said spindle rail, transversely extending bars secured to the lower sides of the spindle rails and connecting said rails together, a longitudinally extending drum shaft journaled in bearings supported by said cross bars, a tape-driving drum mounted on said drum shaft, a series of spindle-driving tapes engaging said drum and the spindles, and a tape-tension means carried by said 55 spindle-rail-supporting brackets.

60 2. A spinning frame comprising a series of vertical standards spaced suitable distances apart and arranged in pairs transversely of the machine, a transverse connecting base piece for 65 each transverse pair of columns and supporting said columns, a transversely extending bridge piece connecting the upper ends of each pair of columns, outwardly extending spindle-rail-sup- 70 porting brackets secured to said columns at each 75 side of the machine frame, a spindle rail on each side of the machine frame and supported by said spindle rail brackets, spindles supported by said spindle rail, vertically movable slides mounted on the said columns, a ring-rail associated with each spindle rail and supported from the adja-

cent vertically movable slides, a rotary oscillating longitudinally extending builder-motion shaft supported in the machine frame, a ring-rail-moving pulley mounted on said shaft for each pair of slides, flexible connections from said pulley to each pair of slides, the connection from one slide contacting the pulley on one side of the center thereof and the connection from the other slide contacting the pulley on the opposite side of the center thereof, the two connections winding on the pulley in the same direction.

3. A spinning frame comprising a frame, a spindle rail on each side of the machine frame, spindles supported by said spindle rails, a rotary oscillating longitudinally extending builder-motion shaft supported in the machine frame, a thread-board for each spindle rail, thread guides carried by said thread-boards, vertically extending rack bars depending from each thread-board, guides for said rack bars mounted in the machine frame, a gear wheel engaging each of said rack bars, a rack bar pulley mounted on the shaft of each of said gears, a thread-board-moving pulley mounted on the oscillatory shaft for each pair of thread-board-supporting rack 20 bars, flexible connections from said rack bar pulleys to the thread-board-moving pulley, the connection from one of said rack bar pulleys contacting the thread-board-moving pulley at one side of its center and the connection from the other rack bar pulley contacting it on the opposite side of its center, both of said connections passing around the thread-board-moving pulley in the same direction.

4. A spinning frame comprising a series of vertical standards spaced suitable distances apart and arranged in pairs transversely of the machine, outwardly extending spindle-rail-supporting brackets secured to said standards at each side of the machine frame, a spindle rail on each side of the machine frame and supported by said spindle rail brackets, spindles supported by said spindle rail, vertically movable slides mounted on the said standards, a ring-rail associated with each spindle rail and supported from the adjacent 45 vertically movable slides, a rotary oscillating longitudinally extending builder-motion shaft supported in the machine frame, a ring-rail-moving pulley mounted on said shaft for each pair of slides, flexible connections from said pulley to 50 each pair of slides, the connection from one slide contacting the pulley on one side of the center thereof and the connection from the other slide contacting the pulley on the opposite side of the center thereof the two connections winding on 55 the pulley in the same direction.

5. A spinning frame comprising a series of vertical standards spaced suitable distances apart and arranged in pairs transversely of the machine, a transverse connecting base piece for 60 each transverse pair of standards and supporting said standards, a transversely extending bridge piece connecting the upper ends of each pair of standards, longitudinally extending roll-stand-supporting members secured to the ends of the bridge pieces directly over the upper ends of the said standards, outwardly extending spindle-rail-supporting brackets secured to said standards at each side of the machine frame, a spindle rail on each side of the machine frame and supported by 65 said spindle rail brackets, spindles supported by said spindle rails, transversely extending bars secured to the lower sides of the spindle rails and connecting said rails together, a longitudinally extending drum shaft journaled in bearings sup- 70 75

- ported by said cross bars, a tape-driving drum mounted on said drum shaft, a series of spindle-driving tapes engaging said drum and the spindles, vertically movable slides mounted on the said standards, a ring-rail associated with each spindle rail and supported from the adjacent vertically movable slides, a rotary oscillating longitudinally extending builder-motion shaft supported in the machine frame, a ring-rail moving pulley mounted on said shaft for each pair of slides, flexible connections from said pulley to each pair of slides, the connection from one side contacting the pulley on one side of the center thereof and the connection from the other slide contacting the pulley on the opposite side of the center thereof the two connections winding on the pulley in the same direction.
6. A spinning frame comprising a series of vertical standards spaced suitable distances apart and arranged in pairs transversely of the machine, a transverse connecting base piece for each transverse pair of standards and supporting said standards, a transversely extending bridge piece connecting the upper ends of each pair of standards, longitudinally extending roll-standing supporting members secured to the ends of the bridge pieces directly over the upper ends of the said standards, outwardly extending spindle-rail-supporting brackets secured to said standards at each side of the machine frame, a spindle rail on each side of the machine frame and supported by said spindle rail brackets, transversely extending bars secured to the lower sides of the spindle rails and connecting said rails together, a longitudinally extending drum shaft journaled in bearings supported by said cross bars, a tape-driving drum mounted on said drum shaft, and a series of spindle-driving tapes engaging said drum and the spindles.
7. A spinning frame comprising a frame, a spindle rail on each side of the machine frame, spindles supported by said spindle rails, a thread board for each spindle rail, thread guides carried by said thread boards, vertical slides connected to each of said thread boards, a ring rail associated with each spindle rail, vertically movable slides connected with each ring rail, a rotary os-

cillatory longitudinally extending builder-motion shaft supported in the machine frame between the ring rails and thread boards, a ring-rail-moving pulley mounted on said shaft for each pair of ring rail sides, flexible connections from said pulley to each pair of said slides, the connection from one slide contacting the pulley on one side of the center thereof and the connection from the other slide at the other side of the frame contacting the pulley on the opposite side of the center thereof, the two connections winding on the pulley in the same direction, a thread-board-pulley on said builder-motion shaft for each pair of thread board slides, flexible driving connections from each of said thread board pulleys to its associated thread board slides, the connection from one of said slides contacting the thread board pulley on one side of the center thereof and the connection from the other thread board slide at the other side of the frame contacting the said pulley on the opposite side of the center thereof, the two connections winding on the thread board pulley in the same direction as the flexible connections are wound on the ring-rail-pulley.

8. A spindle frame comprising a frame, a spindle rail on one side of said frame, spindles supported by said spindle rail, a thread board above the spindle rail, thread guides carried by said thread board, vertical slides connected to the thread board, a ring rail associated with the spindle rail, vertically movable slides connected to the ring rail, a rotary oscillatory longitudinally extending builder-motion shaft supported in the machine frame and extending parallel with the spindle rail, a ring-rail-moving pulley mounted on said shaft for each ring rail slide, a flexible connection from each of said pulleys to each of said slides, a thread-board-moving pulley on said builder-motion shaft for each of said thread board slides, and a flexible driving connection from each of said thread-board-moving pulleys to each of said thread board slides, all of the said flexible connections winding on the pulleys in the same direction.

JOSE SERRA SIO.
